Inventor

J. M. Childers

By Clarence O'Brien
Attorney

UNITED STATES PATENT OFFICE

JOHN M. CHILDERS, OF LENOIR, NORTH CAROLINA

CHAIR

Application filed April 3, 1928. Serial No. 267,093.

The present invention relates to chairs and has for its principal object to provide an article of this character which may be made of any suitable rigid material, such as wood or metal and in which the parts entering into the construction thereof are reduced to a minimum without sacrificing any of the desirable features in the chair, such as attractiveness in appearance, strength and comfort.

10 A further object of the invention is to construct the chair of separate units adapted to be easily and quickly secured together in assembled position and which may also be dismantled so as to enable the chair to be easily 15 and quickly packed for shipping purposes in a relatively small space.

A still further object is to provide an article of this character of a simple and practical construction, which is relatively inexpensive 20 to manufacture and otherwise well adapted for the purposes for which the same is intended.

Other objects and advantages reside in the 25 special construction and combination of the various elements forming the invention, reference being had to the accompanying drawing, wherein:—

Figure 1 is a view in side elevation of a 30 chair constructed in accordance with my invention,

Figure 2 is a view in perspective of the bottom of a chair, and

Figure 3 is a transverse sectional view 35 through one of the chair legs showing the manner in which the leg brace is attached thereto.

Figure 4 is a modified form of combined chair back and rear legs.

Referring now to the drawing in detail, 40 the invention comprises a chair consisting of a back 5, seat 6 and legs 7. Each of these parts are preferably constructed as a separate unit and assembled together to form the completed article in a manner as more fully hereinafter explained.

However, if desired, the rear legs may be 45 cast or otherwise formed as a unit with the back, as illustrated in Figure 4, the legs forming a continuation of the side posts of the back.

The back, seat and legs of the chair may be constructed of either metal, wood or other rigid material and may be of any desirable style or shape to suit the individual case.

The back and seat are preferably secured 55 to each other in any suitable manner, well known in the art, and the legs 7 are secured to the underside of the seat by angle brackets 8 which are bolted as at 9 respectively to the seat at one side of the legs.

Disposed immediately beneath the seat is an upper brace 10, preferably of a continuous strip of strap iron or other strong material and extending about the outer edges of the upper ends of the legs in a manner to 60 substantially enclose the same. It will thus be seen from an inspection of Figure 2 of the drawing that the brackets 8 will prevent the movement of the upper ends of the legs inwardly toward the center of the seat whereas the brace 10 will prevent the outward movement of the legs toward the edge of the seat.

Intermediate the upper and lower ends of 65 the legs 7 is arranged a lower brace 11 extending similarly to the upper brace 10 about the outer edges of the legs whereby to prevent outward spreading movement thereof, said lower brace being preferably inclined 70 downwardly toward the rear as clearly shown 75 in Figure 1 of the drawing.

Each of the braces 10 and 11 are secured 80 to each of the legs by bolts 12 extending through openings formed in the braces and transversely of the legs, the bolts being retained in position by means of nuts 13.

Each of the bolts 12 is provided with a bushing 14 arranged in the opening of the leg, and constructed of metal whereby to 85 prevent loosening of the bolts in the legs, when such leg is constructed of wood.

It will be apparent from the foregoing explanation that the chair constructed in accordance with my invention may be easily 90 and quickly assembled merely by attaching the various bolts to the various parts in the manner indicated the chair may be shipped from the factory in a knock-down condition 95 and assembled at its point of destination and 100

thus enable considerable economy in the shipping thereof.

Furthermore the article will be strong and may be constructed of relatively light weight material, the comfort of the chair depending upon the style and construction of the back and seat thereof.

It is obvious that the invention is susceptible to various changes and modifications without departing from the spirit or scope of the invention as hereinafter claimed, and I accordingly claim all such forms of the device to which I am entitled.

What I claim is:—

An article of furniture of the class described comprising a back and seat arranged in attached position with respect to each other, a plurality of supporting legs extending from the underside of the seat, an angular attaching bracket attached to the inner edge of each of said legs and to the underside of said seat, a pair of continuously formed braces extended about the outer edges of said legs and secured thereto in spaced relation from each other whereby to prevent outward spreading movement of said legs, bolts extended transversely of the legs and the braces and having nuts threaded on one end for securing the legs to said braces, and bushings for the bolts having one end abutting the inner side of said braces, and with their opposite ends forming an abutment for the nut whereby to prevent play between the bolts and the legs.

In testimony whereof I affix my signature.
JOHN M. CHILDERES.
